UNITED STATES PATENT OFFICE

WALTER R. RAMSAUR, OF LOCKPORT, NEW YORK, AND THERON P. CHASE, OF DETROIT, MICHIGAN, ASSIGNORS TO GENERAL MOTORS RESEARCH CORPORATION, OF DETROIT, MICHIGAN, A CORPORATION OF DELAWARE

OIL COOLER

Application filed November 16, 1929. Serial No. 407,730.

It is an object of this invention to provide simple, reliable, inexpensive and efficient cooling or heat-exchange units, suitable for use upon automotive vehicles, for the cooling of lubricating oil or the warming thereof.

These units are intended to be especially suitable for use in an oil cooling system such as that disclosed in pending application 354,245, filed April 11, 1929,—in which a plurality of water pumps are employed; but they may be used, with like advantage, in systems employing a single water pump, as hereinafter referred to, or in systems in which an oil cooling water circuit is maintained entirely distinct from an engine cooling water circuit, or elsewhere.

It is a special object of this invention to provide a cooler of the tubular core type in which a stack or stacks of substantially straight and thin-walled tubes are so disposed that numerous thin streams of oil, or the like, may be passed through between successive pairs of tubes, preferably in orderly "staggered" rows, in such manner as to be repeatedly subdivided by encountering cylindrical surfaces or angular edges of the tubes in the successive rows,—the result being a "scrubbing" action, interrupted by more or less of turbulent flow, which prevents the adhesion of insulating films to the mentioned tubes and assures effective transfer of heat through the thin walls referred to. The novel cooler may incidentally effect a filtering.

This invention aims to provide a relatively great number of thin but broad and staggered oil passages, some or all of which are defined by the walls of elements, such as circular or polygonal tubes, adapted to contribute to the structural rigidity of the entire assembly and to transfer heat to or from water, or the like, advanced through said tubes at a rate and temperature suitable to the desired thermal effect. The cross-sectional configuration of the mentioned tubes may vary and may provide for either comparatively small or comparatively large areas substantially normal to the general direction of oil flow. Either baffling or stream-lining effects, or both, may be obtained; and the oil pressure and consequent velocity may be compara-

tively high, thereby contributing to the mentioned "scrubbing" action. The use of cylindrical tubes of a known type, with hexagonal or other enlarged ends, permits a high oil pressure without risk of collapse, but additional forms illustrated share therewith the merit that the two fluids respectively contact with opposite surfaces of each wall.

This invention may further involve the use of novel diffusion elements in the path of one or both of the mentioned fluids, to assure a comparatively uniform or other predetermined distribution of flow throughout the assembly or unit; and the mentioned diffusing or flow-controlling elements are preferably so formed that their mere insertion, during assembly, assures an advantageous positioning of the same,—no separate securing means or measures being required.

It is a further object of this invention to employ, in combination with the mentioned stacks or sets of straight and circular or polygonal tubes, a single pair of side plates. These are preferably so shaped as to contribute to the structural rigidity of the entire unit, and so spaced as to insure a desired flow past even the external walls of the outermost row of tubes inclosed thereby; and, to cooperate with the mentioned side plates, preferred embodiments of this invention may include one or more pairs of novel headers,—adapted to receive the mentioned diffusion plates and optionally provided with corrugated edges which interfit with the mentioned corrugated walls and/or with the ends of tubes.

Other objects of this invention may be best appreciated from the following description of illustrative embodiments thereof, taken in connection with the appended claims and accompanying drawings.

Figure 1 is to be understood as a side elevational view,—although the disclosed unit may be used in any desired position.

Figure 2A is then a horizontal sectional view, taken somewhat as suggested by the line 2—2 of Figure 1, but with parts broken or cut away, some parts being cut substantially to the levels suggested by the lines 2—2' and 2"—2" of Figure 1.

Figure 2B may be regarded either as a completion of Figure 2A or as a disclosure of similar unit employing different tubes, parts being cut away in an analogous manner.

5 Figure 3A is a vertical sectional view taken substantially as suggested by the lines 3-3 of Figures 1 and 2, with parts broken away.

10 Figure 3B is a vertical sectional view which may be regarded either as a completion of Figure 3A or as a disclosure of alternative features,—parts being cut away in an analogous manner.

15 Figure 4 is a double-scale side elevational view of a single core tube of one type suitable for use herein,—a core being formed by simply securing adjacent edges or abutting faces of the enlarged ends together.

20 Figure 5 is an end view, taken substantially as suggested by the arrow 5 of Figure 4.

25 Figure 6 discloses, in addition to a section which may be regarded as taken in the plane of the line 6-6 of Figure 4, a plurality of alternative cross-sectional outlines such as may be given to tubes, within the scope of the present invention, the walls of said tubes being free from concave surfaces or re-entrant angles.

30 Figures 7 to 9 are respectively diagrammatic elevational views of some of the numerous systems to which the novel oil cooler herein described is suitable.

35 Referring first to features shown in Figures 1, 2A, 3A and 4, an oil cooler unit is shown as comprising, in addition to a stack or set or straight core tubes 10, and corrugated side walls 11, 11', a pair of oppositely concave water headers 12 and 12' (respectively formed from sheet metal and provided with

40 an inlet tubulation 13, and an outlet tubulation 13'), and also with a pair of stamped headers 14 and 14',—respectively provided with threaded openings at 15 and 15'; but it will be recognized that both pairs of headers

45 might be formed of cast metal, and that the means employed to connect pipes therewith is relatively unimportant.

50 The respective core tubes 10 are shown in Figures 2A, 5 and 6 as circular in cross-sectional outline, although provided with slightly enlarged hexagonal end portions 16, 16', adapted to be brought into lateral engagement with like end portions upon adjacent tubes, to produce the known "honeycomb" 55 effect best shown in Figure 2A,—the difference between the outside diameter of the circular portion of each tube and the minimum outside diameter of the hexagonal end portions thereof being such as to provide a de-

60 sired small clearance, compelling the oil to be cooled (or heated) to advance in thin streams therebetween.

65 It will be understood that, upon suitably assembling the requisite number of tubes the enlarged ends of a set thereof may be soldered

70 together by momentary immersion, or united by an equivalent operation; and, to permit the passage of oil not only between the adjacent pairs of tubes but externally of the outermost rows thereof, the walls 11, 11' may be so corrugated, when this effect is desired, as to maintain a substantially uniform distance from the adjacent tubes,—this distance being substantially the same as that between the respective pairs of tubes. In other words, in 75 case the tubes are circular in cross-section, the inner surfaces of the mentioned corrugations may also be circular in cross-sectional outline and of substantially the same external radius, or they may be such as to produce any 80 desired ratio of flow between a corrugated or other wall and adjacent tubes.

85 The respective water header elements 12 and 12' may be so formed as to be interchangeable, each being provided with a concavity 17 of sufficient depth to adapt the same to function as a manifold, and provided also with a peripheral flange 18; the mentioned concavity may be adapted to receive a water-diffusion plate 19, having inwardly or oppositely bent edge portions 20, 20', adapted to establish its position within the concavity 17, spacing said plate away from the ends of tubes 10; and the flange 18 may be provided, along its longer edges, with corrugations 21, adapted to interfit with any corrugations provided by or in the walls 11, 11'. The plate 19 is shown as provided with spaced openings 22; and these, whether uniform or varying in size (to effect a desired distribution of 100 flow), may be so positioned that each opening substantially coincides with a point of junction of three of the hexagonal end portions of the mentioned tubes 10.

105 The respective oil headers 14, 14' may advantageously be so cast or shaped that upper and lower flanges 23, 23' thereof shall interfit with the hexagonal or other enlarged ends of a terminal row of tubes 10, and shall also interfit in interlocking relationship beneath 110 the mentioned flanges 18 upon the water headers 12, 12'; and, if desired, the oil inlet header 14 may receive a diffusion plate 24, provided with openings 26. Whether uniform or non-uniform in distribution and size, these openings correspond in function to those of the mentioned diffuser plate 19.

115 Although satisfactory results have been obtained by the use of tubes and corrugated side plates of exactly the described types, and although substantially uniform and equally spaced openings may be used in the mentioned diffuser plates, (a marginal row of small openings being suggested at 19', Figure 2A) 120 Figures 2B and 3B respectively suggest the use of plates containing openings which are graduated in size and/or distribution,—the more central openings 26b in the plate 19b being smaller than the relatively remote openings 26b', in order that the flow of water 125

through the remote tubes may be substantially equal to or even greater than that through the centrally disposed tubes. Similarly, in Figure 3B, the plate 25b is shown as 5 provided with comparatively small openings 27b, near the middle thereof, and with comparatively large openings 27b' near the edges and corners thereof.

As suggested in Figure 6, a considerable 10 number of alternative cross-sectional outlines may be given to core tubes employed in the described manner, a substantially square outline being suggested at 10a, a diamond-shaped outline at 10b, a lenticular outline at 10c, an 15 elliptical outline at 10d, and ovoidal outline at 10e optionally providing an edge at e,—no end configuration being shown. Any of these 20 outlines may be provided with hexagonal or other laterally-abutting end portions of a 25 suitable type; but it is found advantageous to keep the space between tubes down to $\frac{1}{16}$ inch or less.

Obviously the exact style of corrugation 30 of the reinforcing and flow-controlling side 25 walls 11, 11' may depend upon the cross-sectional configuration of the tubes contacting therewith or spaced therefrom; and the latter need not ordinarily be graduated or varied in style or size as suggested in Figures 2A and 2B. Even if the central parts 35 of the tubes are adapted slightly to collapse laterally, in consequence of changes in the pressure or in the viscosity of the oil, the end portions of a given set of tubes may all 40 alike be hexagonal or square or diamond shaped,—the interfitting parts of the oil headers and the side plates being of corresponding configuration. Extruded tubes with hexagonal ends have been found entirely 45 satisfactory; and it will be noted that, in case ovoidal forms 10e are used, the successive rows thereof may alternate as to the direction in which the comparatively sharp edges of such tubes are disposed,—as suggested near the center of Figure 2A, at e and e'.

It will be recognized as highly advantageous that, in these oil cooling and heat-exchange units, no wall elements are required 50 additionally to the two mentioned side plates, preferably corrugated and interfitting with some or all of the mentioned headers; that, soldering being deemed preferable to any use of gaskets herein, the ends of the terminal 55 rows of tubes may be secured to flanges of the adjacent oil headers, and/or the ends of side rows of tubes may be secured to adjacent side plates (said plates and said headers being preferably about equal in length 60 to said tubes) by the same partial-immersion soldering operation by which an entire set of hexagonal or other enlarged ends is integral- 65 ly united.

The ends of the side plates being prefer- 65 ably receivable within flanges of the oil head-

ers, the roughly rectangular form of the unit shown is favorable to an easy completion of assembling operations by slipping the flanges 18 and 18' of the water headers over parts such as flanges 23, 23' of the oil headers; and 70 it will be obvious that any of the said headers may, according to the intended position of use, be provided with integral or other apertured brackets 30, for the support of the unit. Corrugation of the plate-engaging 75 portions of the flanges 18 obviates necessity for providing flat edge portions upon the corrugated side plates,—which can accordingly be cut from uniform sheet or strip stock; the headers of each pair may be identi- 80 cal in form, that header (if either) into which a distributing plate is inserted in advance of the soldering thereof in place being thereby qualified to serve as an intake; and any desired uniform or non-uniform flow 85 may be provided for by the use of special sizes, shapes and/or distribution of holes in the diffusion plates 19 and 24,—preferably provided with integral positioning means. 90 For example, to offset an inflow of heat from some hot environment, the distribution holes near the periphery of plate 19, in the water inlet header, may be enlarged beyond a size requisite to equality of flow.

The term "water" is herein applied generally to a relatively "thin" heating or cooling fluid, and the term "oil" is intended to include any relatively "thick" or "viscous" fluid to be heated or cooled. It is found best to advance the latter externally of the tubes, 100 in order to obtain the scrubbing effect due to the use of very thin passages therebetween; but the water headers obviously may be entirely omitted when the unit is to be merely immersed as in a cold stream or bath 105 of brine or the like.

Units of the described form admit of the easy application of any desired external insulation and/or reinforcement not shown; the described cross-sectional outlines adapt 110 the tubes to withstand, if necessary, high and/or unequal pressures and effect to some extent automatic equalization of flow spaces between the tubes of the transverse rows,—lateral pressure being diminished with increase of velocity of flow; and a slight lateral collapse of the non-circular forms, varying the extent of the "scrubbed surfaces" 115 provided thereby, may automatically increase the clearance therebetween with increased oil pressure,—the extent of such collapse being variable, in turn, by varying the pressure upon the cooling water.

It is believed that diagrammatic Figures 7 and 8 will be sufficiently explained by the 125 legends thereon,—any oil cooler within the scope of the present invention being suitable for use as suggested at 29, Figure 7, or as suggested at 29', Figure 8, or in any analogous system. Valve 30 in pipe 31, Figure 7, 130

may so open at a predetermined pressure as to by-pass cooler 29 and it may open, at a higher pressure, a return connection 32 to pan 33; and this organization will be seen to be somewhat simpler than that shown in Figure 8,—requiring two oil pumps 34 and 35 and one water pump 36; but the inclusion of a filter 37 in either circuit 38 or circuit 39 should be regarded as entirely optional, in either or any system.

In case the cooler unit is desired to serve also as a filter unit, a valved pressure pipe 40 may be connected with its outlet manifold, and a valved drain pipe 41 may be connected with its inlet manifold, as suggested in Figure 7, any desired pressure means and any desired valve-operating means being used therewith.

Shutters 42 and/or a by-pass 43 may be so provided as to obviate any undue cooling or to facilitate warming of oil, and may be manipulated by suitable manual means and/or by automatic means. For example, a thermostat 44 may render the closing of shutters 42 and/or the opening of by-pass 43 dependent upon the temperature of the cooling water leaving the engine jacket,—by a pull upon a link 45 and/or a link 46. The latter is shown as pivotally connected with an arm 47 of a valve 48. Alternatively or additionally a thermostat 49, responsive to the temperature of the oil that has been acted upon by the "cooler" and/or has entered the engine proper may manipulate said shutter and/or said valve; as by means of thrusts applied through rods 50 and/or 51 (optionally containing springs, not shown).

Figure 9 suggests the use of an oil heater 29a distinct from an oil cooler 29b,—any required pumps being used on either side thereof. The flow of heating and/or cooling fluids and/or oil from a pump 34a may, in this instance, be varied by means such as an exit-oil thermostat 49a. For a heating effect, water may be shunted from the engine jacket, as by way of a pipe 43a, or direct or indirect use may be made of heat from an exhaust pipe 52a. For example, a heating fluid may enter and exit through tubulations 13a and 13a'; but it will be understood that the heat exchange elements 29a and 29a' need not be so separate as Fig. 9 might seem to imply.

Although the foregoing description has included details of but one complete embodiment of this invention, optional features being incidentally suggested, it should be understood not only that various features of this invention might be employed, but also that numerous additional modifications might easily be devised, by workers advised of the foregoing,—all without the slightest departure of the scope of the present invention.

We claim:

1. In a tubular-core oil cooler: a set of parallel tubes arranged in rows; a pair of

side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes. 70

2. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—said headers being substantially identical in form. 75

3. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—said headers being substantially identical in form and shaped to fit over said end portions of said side plates. 80

4. In a tubular-core oil cooler: a set of parallel tubes arranged in rows; a pair of side plates engaging end portions of said tubes; and a pair of oil headers so engaging end rows of said tubes and end portions of said plates as to compel oil advancing between said headers, to pass in streams whose thinness is determined by the cross-sectional configuration and spacing of said tubes, said headers being substantially identical in form and shaped to receive a diffusion plate interfitting therein. 105

5. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—one of said headers containing means for predetermined a diffusion of flow past said tubes. 110

6. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—a dimension of said plates and a corresponding dimension of said headers being substantially the same as the length of said tubes. 125

7. In a tubular-core oil cooler: a set of 130

- parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—said plates being provided with corrugations extending substantially parallel with said tubes. 6
8. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—said plates being provided with corrugations corresponding in curvature with the walls of said tubes. 15
9. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—said plates being provided with corrugations so spaced from said tubes, in an intermediate region thereof, as to permit oil to pass externally of said tubes. 20
10. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—only the ends of side rows of said tubes being secured to said plates. 25
11. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—some of said tubes having rounded surfaces upon flow-receiving sides thereof. 30
12. In a tubular-core oil cooler: a set of parallel tubes arranged in rows; a pair of side plates engaging end portions of said tubes; and a pair of oil headers so engaging end rows of said tubes and end portions of said plates as to compel oil, advancing between said headers, to pass in streams whose thinness is determined by the cross-sectional configuration and spacing of said tubes,—some of said tubes having edges upon the flow-receiving sides thereof. 35
13. In a tubular-core oil cooler: a set of parallel tubes; a pair of side plates engaging end portions of some of said tubes; a pair of oil headers engaging end portions of some of said tubes and end portions of said plates, to compel oil, advancing between said headers, to pass between said tubes in thin streams, for a "scrubbing" effect; and a pair of water headers interfitting with said side plates. 70
14. In a tubular-core oil cooler: a set of parallel tubes; a pair of side plates engaging end portions of some of said tubes; a pair of oil headers engaging end portions of some of said tubes and end portions of said plates, to compel oil, advancing between said headers, to pass between said tubes in thin streams, for a "scrubbing" effect; and a pair of water headers interfitting with said side plates, said water headers being provided with flanges which extend over said side plates. 75
15. In a tubular-core oil cooler: a set of parallel tubes; a pair of side plates engaging end portions of some of said tubes; a pair of oil headers engaging end portions of some of said tubes and end portions of said plates, to compel oil, advancing between said headers, to pass between said tubes in thin streams, for a "scrubbing" effect; and a pair of water headers interfitting with said side plates, said water headers being provided with flanges which extend over said side plates. 80
16. In a tubular-core oil cooler: a set of parallel tubes; a pair of side plates engaging end portions of some of said tubes; a pair of oil headers engaging end portions of some of said tubes and end portions of said plates, to compel oil, advancing between said headers, to pass between said tubes in thin streams, for a "scrubbing" effect; and a pair of water headers interfitting with said side plates, said side plates being corrugated and said water headers being provided with flanges interfitting therewith. 85
17. In a tubular-core oil cooler: a set of substantially parallel tubes; a pair of side plate elements; a pair of oil header elements; and a pair of water header elements,—one of said pairs of elements being provided with means to retain the mentioned parts in assembled relationship. 90
18. A tubular-core oil cooler of the character described in claim 17, in which said plate elements are so corrugated as to predetermine a flow of oil in thin streams past surfaces of said tubes, and in which the last-mentioned pair of header elements is provided with flanges adapted to interfit with corrugations in said plate elements. 115
19. In an oil cooler: headers; flow passage elements adapting the same to function 120
- 60

as a filter; and means, connected with said headers, to effect a reversal of flow therein, for a clearing effect.

20. An oil temperature regulator which 5 includes heat exchanging elements between which there are provided spaces in the neighborhood of $\frac{1}{16}$ " or less in width through which oil is adapted to flow.

21. An oil temperature regulator which 10 includes a plurality of parallel tubes through which a heating and/or cooling medium is adapted to flow, and between which there are provided spaces $\frac{1}{16}$ " or less in width through which oil is adapted to flow.

15 22. In an oil cooler, a plurality of parallel tubes on which there are provided enlarged ends which are united to form a core, plates united to the enlarged ends of the outer side tubes to form side walls of the cooler, and 20 headers united to the sides of the plates and inclosing the outer end rows of the tubes.

23. In an oil cooler, a plurality of parallel tubes on which there are provided enlarged ends which are united to form a core, plates 25 united to the enlarged ends of the outer side tubes to form side walls of the cooler, headers united to the sides of the plates and inclosing the outer end rows of tubes, and headers secured to the ends of the plates and the ends 30 of the first-mentioned headers and inclosing the ends of the tubes.

24. In an oil temperature regulator, a plurality of parallel tubes which are spaced apart for a portion of their length to provide oil passages and plates which form walls 35 of the regulator and in which there are provided corrugations which are so arranged as to permit between the plates and the adjacent tubes a flow of oil comparable to that between the adjacent tubes.

40 In testimony whereof we affix our signatures.
